UNITED STATES PATENT OFFICE.

WILLIAM S. BARTHOLOMEW, OF WYNCOTE, PENNSYLVANIA, ASSIGNOR TO
THE ADAMS & WESTLAKE COMPANY, OF ILLINOIS.

KNOB ATTACHMENT.

SPECIFICATION forming part of Letters Patent No. 707,375, dated August 19, 1902.

Application filed April 16, 1902. Serial No. 103,194. (No model.)

To all whom it may concern:

Be it known that I, WILLIAM S. BARTHOLOMEW, a citizen of the United States, residing at Wyncote, in the county of Montgomery and State of Pennsylvania, have invented certain new and useful Improvements in Door-Knob Attachments, of which the following is a specification, reference being had to the accompanying drawings, forming part thereof.

10 My invention relates to a door-knob attachment wherein the knobs for operating the latch may be applied thereto irrespective of the thickness of the door with which it is used.

The object of my improvement is to produce a device of simple construction and ready application to a door and the like by means of which the knobs or handles may be secured to the frame of a mortise lock or latch by adjustable members so arranged 20 that regardless of the thickness of the door or its mountings within certain limits the knobs may be fastened in place.

Referring to the drawings, Figure 1 is a sectional view through part of a door and the upper end of a mortise-lock, showing my invention applied to a door of extreme thickness. Fig. 2 is a similar view, the door being of decreased thickness. Figs. 3 and 4 are perspective views of opposite sides of a part 30 of the cover-plate. Fig. 5 is a perspective view showing the knob and rose connected. Fig. 6 is a similar view of a detail of construction. Fig. 7 shows a modification.

Similar letters of reference indicate similar parts in the respective figures.

35 Into the edge of a door A is mortised a lock, the frame of which consists of the casing B and cover-plate C. Through the upper part of the lock and also through the door A projects a spindle D for operating the latch or latch-plate E through the medium of the hub or stump F in the ordinary way. Depressions G, concentric with the axis of the spindle D, are formed in the casing B and cover-plate C, the walls of which depressions are threaded. A flanged axial opening g is formed through the bottom of each depression G, which serve as bearings for the hub F. Between the inner faces of the depressions G, 50 which latter form bosses F', extending into the casing, Fig. 4, are placed the arms f of

the hub F and latch-plate E, operated by said arms.

H H, Figs. 1, 2, and 6, are thimbles, each thimble consisting of a circular flange h, 55 threaded to screw into a depression G and having a reduced body h', also threaded. Through each thimble H is an opening of two diameters, the larger opening h² fitting freely around the flange g' in the depression G when 60 the parts are assembled, while the smaller opening h³ is large enough to permit the thimble to be rotated around the square spindle D. Notches h⁴ are made in the thimbles, adapted to receive a suitable tool for rotating 65 them.

I I indicate roses, in this instance of circular form, from the external surface of each of which projects a neck I'. A cylindrical extension I² is formed integrally with each 70 rose on its inner side, in which extension is a bore i, threaded to engage the body h'. The diameter of the extension I² is the same as that of the flange h of the thimble H, the extension having cut thereon a thread of similar pitch that it may enter the depression G, as shown in Fig. 2. A sleeve J, flanged at j, passes through and beyond an axial opening in the rose I and neck I', a knob K being fixed to the projecting portion of the sleeve. 75 In assembling these parts the sleeve J is passed through the rose I until the flange j abuts against the shoulder i² at the base of the bore i. The knob K, having been put on the projecting end of the sleeve and moved 80 inwardly until it reaches the neck I', a pin, screw, or other fastening is employed to secure the knob in position. A square hole extends through the sleeve J, through which the square spindle D may slide independently in an axial direction. 85

In practice a hole is bored through the door of a size sufficient to admit the cylindrical extensions I², and the lock is mortised in as usual. The thimbles H are then inserted in 95 the circular opening and their flanges h screwed into the depressions G. A rose I then follows on each side of the door, the cylindrical extensions I² of said roses entering the circular opening at opposite ends, and on 100 turning each rose the threaded bore i will engage the threaded body portion of the thim-

ble H on its side of the door. Continued rotation of the roses will cause them to bear firmly against the respective sides of the door. A screw L, passed through a hole in each rose 5 and into the door, prevents backward rotation of the rose. The spindle D may be inserted in the lock immediately after placing it in the door or before the last rose is put in place.

From Figs. 1 and 2 it will be seen that 10 whatever the thickness of door within certain normal limits no difficulty will be experienced in attaching my improvement. Should the door be thin, as in Fig. 2, the extensions I² will follow the thimbles H into the depressions G. In a thick door if only a few threads of each part are engaged, the knobs will be sufficiently held.

An important feature of my invention consists in the application of the thimble H between the rose and the lock. By its use a double telescopic joint is produced, giving a wider range of adjustment than would be possible if the extensions I² were screwed directly into the lock.

25 Where but one knob is required, the hole for the projection I² is made in one side of the door only and a plug H', similar to the one seen in Fig. 7, substituted for the thimble H in the unused depression G.

30 It is to be understood that the word "rose" found in the claims is intended to cover any means for rotating the cylindrical extension I².

I do not restrict myself to the exact details 35 of construction, combination, and arrangement herein set forth, it being obvious that minor variations thereof not involving the exercise of invention may be made by the skilled mechanic, and such departures from 40 what is herein described and claimed not involving invention I consider as within the scope and terms of my claims.

Having thus described my invention, I claim—

45 1. In combination, a lock-casing having a threaded depression in its side, a rose provided with an integral extension having a threaded bore and adapted under certain conditions to enter said depression in the lock-casing, and a threaded thimble connecting said depression with said extension, substantially as set forth.

50 2. In combination, a lock-casing provided with a threaded depression in its side, a rose having an inwardly-projecting cylindrical extension with a threaded bore and being also circumferentially threaded to adapt said extension to engage under certain conditions

the said threaded depression, and a threaded thimble connecting said depression with said 60 extension, substantially as set forth.

3. In combination, a lock-casing having a threaded depression in its side, a cylindrical extension projecting inwardly from a rose, having a threaded bore and being circumferentially threaded, and a threaded thimble of greater diameter at one end than at the other, and adapted to connect said depression with said cylindrical extension, substantially as 65 set forth. 70

4. In combination, a lock-casing having a threaded depression in its side, a rose provided with an extension having a threaded bore, a thimble having two diameters for connecting said casing with said extension, a 75 sleeve passing through the rose and adapted to rotate therein, and a knob or handle secured to the sleeve, substantially as set forth.

5. In combination, a lock-casing having a threaded depression in its side, a rose having 80 a cylindrical extension projecting inwardly and provided with a threaded bore, a thimble, having a greater diameter at one end than at the other, for connecting the casing with the rose, a polygonally-bored sleeve passing 85 through the rose and adapted to rotate therein, a knob or handle secured to the sleeve, and a spindle, polygonal in cross-section, adapted to slide in the sleeve, substantially as set forth. 90

6. In combination with a lock-casing and its cover-plate, each having a threaded depression G formed with a flanged axial opening g, a hub or stump for operating a latch, said hub being journaled in the flanged openings g, substantially as set forth. 95

7. In combination in a lock, a casing and its cover-plate, each having a threaded depression formed therein, two thimbles, each being of greater diameter at one end than the other and adapted to engage each with one of said depressions, a rose on each side of the lock provided with a cylindrical extension having a threaded bore to engage the thimble on the same side of the lock, a sleeve passing 105 through each rose and adapted to rotate therein, a knob or handle secured to each sleeve, and a polygonal spindle adapted to slide in a similarly-shaped bore in each sleeve, substantially as set forth. 110

In testimony whereof I hereunto set my hand and seal.

WILLIAM S. BARTHOLOMEW. [L.S.]
